A. BOLTZ

PUZZLE

Filed Dec. 27, 1922

FIG. 1.

FIG. 2.

Inventor
Adam Boltz
By his Attorney
Edgar Pates

Patented June 30, 1925.

1,543,693

UNITED STATES PATENT OFFICE.

ADAM BOLTZ, OF GLENDALE, NEW YORK

PUZZLES

Application filed December 27, 1922. Serial No. 609,176.

To all whom it may concern:

Be it known that I, ADAM BOLTZ, a citizen of the United States, and residing at Glendale, in the county of Queens and State of New York, have invented certain new and useful Improvements in Puzzles, of which the following is a specification, such as will enable those skilled in the art to which it appertains to make and use the same.

This invention relates to puzzle devices designed to amuse both young and old; and the object of the invention is to provide a device of this class which is simple in construction, efficient in use and intricate to solve; and with this and other objects in view, the invention consists in a device of the class specified, constructed as herein-after described and claimed.

20 The invention is fully disclosed in the following specification, of which the accompanying drawing forms a part, in which the separate parts of my improvement are designated by suitable reference characters in
25 each of the views, and in which:—

Fig. 1 is a plan view of my improved puzzle device; and,

Fig. 2 is a central transverse section of the device shown in Fig. 1, the section being on the line 2—2 of Fig. 1.

In practice I provide a substantially circular casing 5 preferably composed of sheet metal stamping, and comprising a bottom 6 and a wall or rim portion 7, which is beaded at the top as shown at 8 and the beaded portion 8 may be wrapped around a reinforcing ring 9 if desired. Mounted in the casing 5 is a puzzle body 10 which may be composed of any suitable material, but is preferably composed of sheet metal, fashioned to form a substantially disk-shaped body having a rim portion 11 and a bottom 12, and the body 10 is fashioned to form four substantially semi-circular depressed portions 13, joined together as indicated at 14 and all of which communicate with a central chamber 15. Centrally of each of the semi-circular portions 13 are upwardly pressed inverted disk-shaped members 16 which form around said members, channels 17 in which a spherical member 18 is adapted to pass, said member being preferably a small shot.

The bottom 12 of the body 10 centrally of
55 the chamber 15 of said body is pressed up-

wardly into approximate conical formation as shown at 19, and this upwardly pressed portion is very slight in comparison with the member 16 and centrally of the upwardly pressed portion 19 is a downwardly pressed portion 20, which forms a recess or aperture 21 at the peak of the upwardly pressed portion 19. It will be noted that the walls of the semi-circular portions 13 and members 16 are preferably flared in order to produce a neat and finished appearance, and also to permit of the movement of the spherical member 18 freely through the channels 17, and in the chamber 15 and over the members 16 if desired.

Mounted in the casing 5 above the body member 10 is a transparent panel 22, and it will be noted that the body portion 8 of the casing serves to hold the transparent panel as well as the body 10 in position within the casing. If desired, the top face of the body 10 may be colored as well as the top face of the member 16, and the colors may be different as applied to the different surfaces to give an attractive appearance to the puzzle and it will also be apparent that advertising or other matter in picture or other form may be applied to the top face of the body 10 if desired. 80

The solution of the puzzle consists in placing the spherical member 18 in the recess or aperture 21 at the peak of the upwardly pressed portion 19 centrally of the chamber 5 and this is accomplished by manipulating the casing 5 to bring the ball or spherical member into this position, and due to the curvatures of the channel 17 as well as the upwardly pressed portion 19, it is difficult to place the spherical member in said aperture. It will be understood that my invention is not necessarily limited to the specific construction of the casing herein shown and described nor to the specific form of the body member 10, or the arrangement of the separate projecting members therein, and various changes in and modifications of the invention herein shown and described may be made within the scope of the appended claims without departing from the spirit of my invention or sacrificing its advantages.

Having fully described my invention, what I claim as new and desire to secure by Letters Patent, is:—

1. A puzzle device of the class described, 110

- comprising a casing provided with a plurality of semi-circular channels communicating centrally of the casing, the central portion of the casing being provided with an 5 upstanding member having a recess at the peak thereof, and a member movably mounted in the casing and adapted to be placed in said recess.
2. A puzzle device of the class described, 10 comprising a casing provided with a plurality of semi-circular channels communicating centrally of the casing, the central portion of the casing being provided with an upstanding member having a recess at the 15 peak thereof, a member movably mounted in the casing and adapted to be placed in said recess, said casing being open at the top and the top of said casing being closed by a transparent panel, adapted to prevent 20 the displacement of said member in the manipulation of the puzzle.
3. A puzzle device of the class described, 25 comprising a casing having an upwardly directed rim or wall, a body member mounted in the casing, said body member being fashioned to form a plurality of substantially semi-circular channels placed in communication centrally of said body member, and the central portion of said body member being pressed upwardly and provided at the peak thereof with a recess, and a member mounted to move within said body and adapted to be placed in said recess.
4. A puzzle device of the class described, 35 comprising a casing having an upwardly directed rim or wall, a body member mounted in the casing, said body member being fashioned to form a plurality of substantially semi-circular channels placed in communication centrally of said body member, and the central portion of said body member being pressed upwardly and provided at the peak thereof with a recess, a member mounted to move within said body and adapted to be placed in said recess, and a transparent panel mounted upon the top of said 45 body.
5. A puzzle device of the class described, 50 comprising a casing having an upwardly directed rim or wall, a body member mounted in the casing, said body member being fashioned to form a plurality of substantially semi-circular channels placed in communication centrally of said body member, and the central portion of said body member being pressed upwardly and provided at the peak thereof with a recess, a member mounted to move within said body and adapted to be placed in said recess, a transparent panel mounted upon the top of said 55 body.

body, and means for retaining said panel and said body in the casing.

6. A puzzle device of the class described, 65 comprising a sheet metal casing, a sheet metal body mounted in said casing and adapted to fit snugly therein, said body being fashioned to form a plurality of semi-circular channels communicating centrally of said body, the central portion of said body being pressed upwardly to form a substantially conical member at the top of which is a recess, and a spherical member mounted to move within said body and adapted to be placed in said recess.

7. A puzzle device of the class described 75 comprising a substantially circular disk-shaped body open at one side face thereof, said body being fashioned to form in the bottom face thereof a plurality of semi-circular grooves opening into and communicating with the central portion of said body, said grooves being partially formed by raised cylindrical bodies located centrally of the semi-circular grooves, the central portion of said body being raised and provided with a recess at the top of the raised portion.

8. A puzzle device of the class described comprising a substantially circular disk-shaped body open at one side face thereof, 90 said body being fashioned to form in the bottom face thereof a plurality of semi-circular grooves opening into and communicating with the central portion of said body, said grooves being partially formed by raised cylindrical bodies located centrally of the semi-circular grooves, the central portion of said body being raised and provided with a recess at the top of the raised portion, and the outer walls of the grooves being of greater height than the walls 95 formed by said cylindrical members.

9. A puzzle device of the class described comprising a pan-shaped body, the top face of which is fashioned to form four radially and circumferentially spaced projecting cylindrical members around which are grooves of semi-circular formation said grooves opening into the central portion of said body, the central portion of the body being fashioned to form a conical projection at the peak of which is a recess and a spherical member adapted to operate in the grooves of said body and over said conical projection and to be placed in said recess of the 105 puzzle.

In testimony that I claim the foregoing as my invention I have signed my name this 26th day of December, 1922.

ADAM BOLTZ.
